METAL ROLLING MILL SCREW DOWN CONTROL

Application filed December 15, 1928. Serial No. 326,333.

Our invention relates to a method of and apparatus for rolling metal, and more particularly to a method of and apparatus for reducing metals and other materials to 5 sheets or strips of uniform gauge or thickness.

The usual means for reducing metals and other materials to sheets or strips comprises a plurality of mills arranged in tandem, 10 each mill consisting of two or more metal reducing rolls, the metals or other materials being passed between the reducing rolls of the mills successively, each mill reducing the thickness or gauge of the materials a certain amount until the sheet or strip emerges 15 from the last or final mill with the desired thickness or gauge.

The gauges of sheets or strips of material delivered by a final mill of a series must be 20 kept constant within very narrow limits in order to meet the standard gauge variations allowed by the trade, and in order to bring this about the several causes of gauge variations must be kept constantly under control.

25 There are four major causes of gauge variations in the rolling of materials in a rolling mill; first, that due to variations in the gauge of the materials entering between the rolls of the mill; second, that due to variations in the hardness of the material being rolled; third, that due to variations in the roll temperatures; and fourth, that due to changes in roll contours during the rolling processes.

35 Of the several causes of gauge variations, we shall concern ourselves chiefly in the present application with those due to variations in the gauge of material entering between the rolls of a mill and to variations in the hardness of the material.

In the usual mill for rolling metal there is 40 provided means for varying the size of the pass or opening between the metal reducing rolls, and the mill operator constantly measures the thickness of the material delivered by the mill and adjusts the size of the pass or opening, in order to correct any variations which take place in the gauge of the material delivered. If the material delivered to the mill is of a constant gauge and

of uniform hardness and temperature, and the temperature of the rolls remains constant, then the size of the pass can be adjusted to bring about the desired reduction and no changes or adjustments thereafter 55 will be necessary. We have found, however, that when material of greater or less thickness or gauge, or of variable hardness, is delivered to the mill the gauge of the material delivered by the mill varies regardless of 60 the fact that no apparent change takes place in the size of the pass between the rolls of the mill. This is chiefly due to the fact that in rolling materials the spring or elasticity of the mill itself is such that variations in the gauge of the material entering 65 persist, in like variations of gauge in the material leaving the mill in a more or less fixed percentage rate, while where the material is of variable hardness the resistance 70 offered to the rolls of the mill varies, with resulting changes in the gauge of the material delivered.

It is, in general, an object of the present invention to provide a method and means for controlling the amount of reduction brought about by a rolling mill, in order to deliver material from the mill having a uniform and constant gauge or thickness.

In a more specific aspect, it is an object 75 of the present invention to provide a method and means for compensating for changes in the amount of spring taking place in a mill due to differences in the amount of reduction which takes place in the material 80 passing through the mill.

A further object of the invention is to provide means for constantly gauging the material acted on by a rolling mill and opening or closing the pass between the rolls according to the gauge of the material.

A still further object of the invention is to provide a mill in which the size of the pass or opening between the metal reducing rolls may be adjusted when the material 95 starts to pass through the mill, and in which the gauge of the material will thereafter be kept constant without further attention on the part of the operator.

To these and other ends, the invention 100

consists in the novel features and combination of parts to be hereinafter described and claimed.

In the drawings,
5 Fig. 1 is a side elevation of a rolling mill showing a preferred form of our invention used in connection therewith;

Fig. 2 is an end view of the same;
10 Fig. 3 is a view of a device used for gauging the material acted on by the mill; and

15 Fig. 4 is a view of an electric circuit used in connection with the controlling device.

In the above description of the nature and objects of our invention, we have referred to the usual arrangement of mills in a tandem in metal reducing, and while our invention may be carried out with such an arrangement of mills it is by no means limited thereto but is of equal utility in instances where but a single reduction of the material takes place, as for example, where it passes through a single mill.

It will be also understood that our invention is not limited to a mill or mills having 25 any particular type or arrangement of rolls therein, and thus while we shall describe our invention in connection with a two-roll mill, which is one of the simplest forms of mills in use, it will be understood by one skilled in the art that the invention may be 30 carried out with cluster mills, four-high mills, and various other forms.

Referring then to the drawings in which we have shown a preferred embodiment of 35 our invention, the reference numeral 10 indicates, in general, a mill stand or frame, having mounted therein a lower roll 11 and an upper roll 12, the lower roll being mounted in relatively fixed bearings 13, while the 40 upper roll is mounted in adjustable bearings 14.

The material being acted on by the rolls 11 and 12 enters between these rolls at A 45 from between the rolls with a final thickness T^2 , the amount of reduction being the difference between these two thicknesses. It will be understood that in practice a plurality of mills, such as that shown in Fig. 1, 50 may be provided and arranged in tandem, and that the material may pass successively through these mills, each mill reducing the material a predetermined amount. The amount of reduction brought about by each 55 mill depends primarily upon the size or opening of the pass between the metal reducing rolls of the mill, and where a tandem of mills is used the operator adjusts the rolls of the various mills of the tandem by 60 hand to bring about a desired amount of reduction in each mill, being guided in controlling the amount of reduction by the character of the material being acted on by the mills and the desired gauge in the material emerging from the mills.

In order to ensure that the material passes from each mill with the desired gauge, and in order to avoid the usual hand controlled methods for controlling the amount of reduction which depend for success upon the skill 70 of an operator, we propose to control the size of the pass or opening in the mill, or tandem of mills, by suitable means, the operation of which is controlled by the thickness or gauge of the material acted on. 75 We prefer to control the size of the pass of a mill by means which is controlled by the thickness or gauge of the material as it leaves the mill. In carrying out our invention, we provide power means for adjusting 80 the sizes of the passes in a mill or mills, which may be in the form of hydraulic motors, electric motors, or other suitable prime movers, and control the operation of these means by a device which gauges the 85 material passing from the mills. As a suitable and preferred means for carrying out our invention, we shall now describe a mill in which the size of the pass is controlled 90 electrically.

Referring again to the drawings, the reference numerals 15 and 16 indicate adjusting screws mounted in threaded openings in the upper ends of spaced frame parts 17 and 18, screws 15 and 16 being provided with non-circular ends 19 and 20, for the reception of a wrench, by means of which the screws may be adjusted in frame 10 to move the roll 12 towards or away from roll 11. Mounted on the upper ends of frame parts 17 and 18 are 100 brackets 21 and 22, provided with bearings 23 and 24 for screws 15 and 16, bearings 23 and 24 being spaced from the upper ends of frame parts 17 and 18.

Between bearing 23, on bracket 21 and the 105 adjacent upper end of frame part 17, is a rotatable sleeve 25 mounted on and surrounding screw 15, sleeve 25 being provided with a screw 26 having an inner end 27, received in a longitudinally extending slot 28 110 in screw 15. On the lower end of sleeve 25 is a worm wheel 29 having in engagement therewith a worm 30 mounted on the shaft 31 of reversible electric motor 32, shaft 31 115 of motor 32 extending transversely of frame 10 and having mounted on the opposite end thereof from motor 32 a second worm 33 in engagement with a worm wheel 34 mounted on the lower end of sleeve 35, which is received on screw 16, below bracket bearing 24 120 and is provided with a screw (not shown) similar to screw 26 in sleeve 25, which similarly engages a longitudinally extending slot in screw 16. It will be readily understood without further description that upon 125 rotation of motor 32, sleeves 25 and 35 are rotated, thus producing rotation in screws 15 and 16, through the medium of screws 26 and longitudinally extending slots 27, the connection between sleeves 25 and 35 and 130

screws 15 and 16 by means of screws 26 and slots 27 permitting longitudinal movement of screws 15 and 16 relatively to sleeves 25 and 35.

5 Generally speaking, we propose to provide means for constantly gauging the material passing from the mill or mills, and controlling the operation of the motor provided for adjusting the rolls by suitable 10 connections with the gauging means.

A suitable and preferred arrangement for this purpose is shown in Figs. 1, 3 and 4 of the drawings, being designated generally by the reference character 36, and comprising 15 gauging device 37, which controls the operation of switch 38, the latter being connected by suitable electrical connections 39 to motor 32.

Gauging device 37 comprises a pair of 20 arms 40 and 41 pivotally connected together at 42, and having on their opposite ends from pivot 42 a pair of gauging rolls 43 and 44, between which the strip or sheet of material passes as it emerges from between 25 the rolls of the mill. Mounted on arm 40 is a collapsible bellows or sylphon 45 filled with a suitable liquid which will conduct electricity, such as a salt water solution, and bellows 45 being connected by means of 30 pipe 46 to liquid switch 38 which, in general, may be made of a tube 47 of glass or other suitable insulating material, and which is provided with oppositely disposed sealed-in contacts 48 and 49, above which 35 are mounted another pair of oppositely disposed sealed-in contacts 50 and 51. Arms 40 and 41 are urged together by relatively stiff tension spring 52, which is connected to arms 40 and 41 in any suitable or preferred 40 manner. Mounted in a threaded opening in arm 41 is an adjusting screw 53, having a ball point 54 bearing against the upper part of sylphon 45, sylphon 45 being provided with a filling plug 55.

45 In order that the gauging device may be sensitive to small changes in the thickness of the material passing between the gauging rolls, it is proposed to provide a sylphon which has a cross-sectional area many times 50 greater than the cross-sectional area of the liquid switch. For example, if the area of the bellows is one thousand times the area of the bore of the tube 47, a movement of the top of the bellows of .001 of an inch will 55 move the surface of the liquid in the tube one inch. Accordingly, if the terminals 48 and 49 are spaced a distance of one inch from terminals 50 and 51, a very small movement of roll 43 relatively to roll 44 will 60 produce sufficient movement on the part of the liquid column to control the passage of an electric current between the terminals. Normally, when contacts 48 and 49 are submerged in the liquid and contacts 50 and 51 65 are above the liquid, the motor will be at

rest and the rolls of the mill will remain at a constant relative adjustment.

If the material discharged by the rolls of the mill becomes of increased gauge, it is apparent that rolls 43 and 44 will be separated from one another, permitting the level of the liquid in tube 47 to drop and opening the circuit in which the contacts 48 and 49 are connected, this circuit being such that through a relay the main switch controlling 70 the operation of motor 32 is closed, bringing the motor into rotation, and through the medium of sleeves 25 and 35 producing rotation in screws 15 and 16 and movement of the rolls towards one another, thus reducing the gauge of the material as it emerges from the rolls and permitting the rolls 43 and 44 to approach one another, whereupon the liquid rises in tube 47 until it again closes a circuit in which contacts 48 and 49 80 are placed, opening the main switch and stopping the motor. In case the gauge of the material becomes less than it is desired, the rolls 43 and 44 approach one another, thus forcing the liquid out of sylphon 45 85 and into tube 47 until it bridges the gap between contacts 50 and 51, which through a suitable relay close another main switch, which causes the operation of motor 32 in a reverse direction, and finally the separation of rolls 11 and 12 to bring about a greater gauge of the material discharged 90 from between the rolls.

The mill may be set to deliver material of a particular thickness by placing a piece 100 of material of the desired thickness between rolls 43 and 44, and then adjusting screw 53 until the liquid in tube 47 is midway between contacts 48 and 50.

When the area of the sylphon is one thousand times the area of the bore of the tube and the terminals are placed one inch apart in tube 47, a variation in the material passing between the rolls 43 and 44 above or below a desired thickness sufficient to bring 105 about a movement of .0005 at the top of the bellows will cause the actuation of motor 32 to readjust the pass between rolls 11 and 12 to bring the thickness of the material back to that desired.

110 Any suitable form of relays and main switches for causing the actuation of the motor in reverse directions may be provided, that shown in Fig. 4 forming an efficient means for this purpose. Referring then to 120 Fig. 4, the reference numerals 56 and 57 indicate a pair of main line wires leading to any suitable source of electrical energy, wire 56 being connected by lead 58 to terminal 59 of switch 60, and to terminal 61 of switch 62. Main line wire 57 is connected by lead 63 to terminal 64 of switch 60 and terminal 65 of switch 62. Terminal 66 of switch 60 and terminal 67 of switch 62 are connected by a common lead 68 to 125 130

motor 32, while terminal 69 of switch 60 and terminal 70 of switch 62 are connected by a common lead 71 to motor 32. Switches 60 and 62 are operated by means of sole-
5 noids 72 and 73, respectively, and are each normally maintained in open position by means of springs 74 and 75. Solenoid 72 is provided with a lead 76 connected to one wire 77 of the low voltage line, while sole-
10 noid 73 is supplied with a lead 78 connected to lead 76, and likewise to low voltage wire 77. The other lead 79 from solenoid 72 is connected to a terminal 80 of relay switch 81, while the other wire 82 of solenoid 73
15 is connected to a terminal 83 of relay switch 84. Terminal 85 of relay switch 81 and terminal 86 of relay switch 84 are connected by a common lead 87 to wire 88 of the low voltage line. Relay switch 81 is nor-
20 mally held in open position by means of spring 89, while relay switch 84 is normally urged into closed position by means of spring 90, relay switch 84 being held in open position by means of solenoid 91, which is
25 connected to contacts 48 and 49 in switch 38, these contacts being normally bridged by the liquid in switch 38, and permitting the flow of current through lead 92 connected to wire 77 and through the lead 93 connect-
30 ed to wire 88, lead 93 passing to switch contact 49, while contact 48 is connected to solenoid 91 by means of lead 94. Relay switch 81 is closed by means of solenoid 95, which is connected to low voltage line
35 wire 77 by means of lead 92 and to contact 50 by means of lead 96, contact 51 being connected to the low voltage line wire 88 by means of lead 97.

It will be readily understood that, when
the liquid in tube 47 is of sufficient height
to bridge the gap between contacts 48 and
49, current flows from lead 93 from low
voltage line wire 88, through the switch 38
and lead 94 to solenoid 91, and thence
45 through lead 92 to low voltage line wire 77,
thus energizing solenoid 91 and holding
switch 84 in open position. When the level
of the liquid in tube 47 falls below contacts
48 and 49, the circuit leading to solenoid 91
50 is opened, thus permitting spring 90 to close
switch 84 and permitting the flow of cur-
rent through solenoid 73, energizing the lat-
ter and causing switch 62 to close, thus per-
mitting current to flow through motor 32
55 and to produce rotation in screws 15 and 16
to cause an approaching movement between
rolls 11 and 12.

If the liquid level in tube 47 rises high enough to bridge the gap between contacts 50 and 51, the circuit leading to solenoid 95 is closed, thus energizing solenoid 95 and causing the closing of switch 81, which permits current to flow through solenoid 72 to close switch 60, which in turn permits the flow of current into motor 32, the flow of

current in this case being in the reverse direction and producing movement in motor 32 in the reverse direction to cause rotation in screws 15 and 16 to bring about the separation of rolls 11 and 12 until the gauge of the material delivered by the mill becomes normal, whereupon the level of the liquid in tube 47 falls and opens the circuit. If desired, a double throw double pole reversing switch 98 may be provided in the main line for causing the actuation of motor 32 by hand, while a single throw double pole switch 99 may be provided in the low voltage line for interrupting the flow of current therethrough.

therethrough. From the above description of the nature of our invention and the preferred means for carrying it out, it will be seen that we have provided a means for constantly gauging the thickness of material emerging from between the rolls of a mill, together with means for causing adjustment of these rolls to correct variations in the gauge of the material as these variations may occur. The preferred embodiment disclosed herein is capable of working within varying limits, it being possible with a large ratio between the areas of the sylphon and liquid to correct extremely small variations in the gauge of the material. Thus it will be seen that we have provided a method and means whereby a rolling mill may be set to deliver material of a particular gauge, and in which variations in the thickness or hardness of materials delivered to the mill are automatically compensated for, so that the material emerges from between the rolls of the mill with a constant gauge.

with a constant gauge. While we have shown a preferred embodiment of our invention, it is to be understood that the same is not to be limited to all the details shown but is capable of modification and variation within the spirit of the invention and the scope of the appended claims. 105 110

What we claim is:

What we claim is:

1. In a gauge controlling system for a rolling mill wherein the size of the pass between a pair of metal reducing rolls is adjusted by a reversible electric motor, the combination of means for engaging the material being rolled on opposite sides thereof, a fluid chamber on said means, a liquid level operated reversing switch for said motor connected to said fluid chamber, and means on said material engaging means cooperating with said fluid chamber for controlling the liquid level in said switch. 115 120

the liquid level in said switch. 2. In a gauge controlling system for a rolling mill wherein the size of the pass between a pair of metal reducing rolls is adjusted by a reversible electric motor, the combination of a pair of arms pivotally connected together, means on said arms for engaging the material on opposite sides thereof, a fluid chamber on one of said arms, a

liquid level operated reversing switch for controlling said electric motor, a connection between said fluid chamber and reversing switch, and means on said arms cooperating with said fluid chamber for varying the liquid level in said reversing switch.

3. In a gauge controlling system for a rolling mill wherein the size of the pass between a pair of metal reducing rolls is adjusted by a reversible electric motor, the combination of a pair of arms pivotally connected together, material engaging rolls on the ends of said arms, means for urging said rolls into contact with opposite sides of the material, a collapsible bellows on one of said arms, an adjustable element on the other of said arms in contact with a part of said bellows, a liquid level motor controlling switch, and a connection between said bellows and switch.

4. In a gauge controlling system for a rolling mill wherein the size of the pass between a pair of metal reducing rolls is adjusted by power operated means, the combination of liquid level means for controlling the operation of the power means, and means for varying the liquid level in accordance with the gauge of the material acted on by the rolls.

30 5. In a gauge controlling system for a rolling mill wherein the size of the pass between a pair of metal reducing rolls is adjusted by a reversible electric motor, the combination of a liquid level controlled switch for controlling the operation of said motor, and means for varying the liquid level in said switch according to the gauge of the material acted on by said rolls.

6. In a gauge controlling system for a rolling mill wherein the size of the pass between a pair of metal reducing rolls is adjusted by a reversible electric motor, the combination of a pair of relatively movable members between which material may be received to be gauged, a liquid chamber on one of said members, means on the other of said members cooperating with the liquid contents thereof according to the gauge of the material received between the members, and a second liquid chamber connected to said first named chamber, the liquid level in said second named chamber being controlled by the amount of liquid retained in the first named chamber, and means controlled by the liquid level in said second named chamber for controlling the operation of the motor.

7. In a gauge controlling system for a rolling mill wherein the size of the pass between a pair of metal reducing rolls is adjusted by a reversible electric motor, the combination of a pair of relatively movable members between which material may be received to be gauged, a collapsible liquid chamber on one of said members, said chamber being of relatively large cross-sectional area, means on

the other member cooperating with the liquid chamber to collapse the same to vary the liquid contents thereof according to the gauge of the material received between the members, and a second liquid chamber connected to said first named chamber, said second liquid chamber being of relatively small cross-sectional area, the liquid level in said second named chamber being controlled by the amount of liquid retained in the first named chamber, and means controlled by the liquid level in the second chamber for controlling the operation of the motor.

In witness whereof, we have hereunto set our hands this 13th day of December, 1928.
